[57] CLAIM

The ornamental design for shoe signage, as shown and described.

DESCRIPTION

FIG. 1 is a perspective view of a shoe signage showing our new design, the shoe shown in broken lines in this and the remaining figures is for illustrative purposes only and forms no part of the claimed design;

FIG. 2 is a front elevational view thereof;

FIG. 3 is a right side elevational view thereof, the left side elevational view being substantially a mirror image thereof;

FIG. 4 is a top plan view thereof;

FIG. 5 is a bottom plan view thereof;

FIG. 6 is a perspective view of a shoe signage showing our new design, the shoe shown in broken lines in this and the remaining figures is for illustrative purposes only and forms no part of the claimed design;

FIG. 7 is a front elevational view thereof;

FIG. 8 is a top plan view thereof;

FIG. 9 is a bottom plan view thereof;

FIG. 10 is a left side elevational view thereof; and,

FIG. 11 is a right side elevational view thereof.
